UNITED STATES PATENT OFFICE.

FREDRICK L. JEFFERIES, OF GRANITE CITY, ILLINOIS, AND WILLIAM SPAIN, OF ST. LOUIS, MISSOURI, ASSIGNEES TO CORN PRODUCTS REFINING COMPANY, A CORPORATION OF NEW JERSEY.

FILLING APPARATUS.

1,079,496.

Specification of Letters Patent. Patented Nov. 25, 1913.

Original application filed February 23, 1911, Serial No. 610,291. Divided and this application filed November 6, 1911. Serial No. 658,655.

To all whom it may concern:

Be it known that we, FREDRICK L. JEFFERIES and WILLIAM SPAIN, citizens of the United States, residing at Granite City, in the county of Madison and State of Illinois, and St. Louis, Missouri, respectively, have invented certain new and useful Improvements in Filling Apparatus, of which the following is a specification.

10 Our invention relates to filling apparatus and has for its object to provide an apparatus, intended particularly for filling cans or other receptacles with liquid, having the several novel and improved features to be 15 hereinafter described and claimed.

The present application is a division of our application entitled Can filling apparatus filed February 23, 1911, and bearing Serial No. 610,291, in which is described and 20 claimed a can filling machine comprising apparatuses operating together automatically for first weighing the empty cans, then introducing therein measured volumes of the liquid, then introducing more of the liquid 25 in dribble streams, and thereafter, by means of certain weighing mechanisms, shutting off the dribble streams when the cans have received given quantities of the liquid measured by weight; the machine also comprising 30 means for feeding the empty cans into position to be filled and discharging them when the filling operation is complete. The present application concerns only the instrumentalities employed for introducing the 35 liquid into the receptacles, no claim being made herein either to the machine as a whole or to the weighing or can feeding mechanisms, these inventions being claimed in the parent application.

40 While the inventions which form the subject matter of the present divisional application are perhaps of particular value and utility when employed to form a part of a machine of the character described in our 45 former application, it will be obvious from the following description that they might be used in other connections.

Our invention herein sought to be patented is illustrated as embodied in a can filling 50 machine of preferred construction in the accompanying drawings of which—

Figure 1 is a vertical sectional view taken

centrally through the machine, Fig. 2, a detail in elevation of the dribble valve opening roller; Fig. 3, a sectional view taken on line 3—3 of Fig. 2, looking in the direction of the arrows; Fig. 4, a plan view of the machine; Fig. 5, a sectional plan view on line 5—5 of Fig. 1; Fig. 6, a detail section on line 6—6 of Fig. 5; Fig. 7, a fragmentary sectional plan taken on line 7—7 of Fig. 1; Fig. 8, a fragmentary sectional view taken on line 8—8 of Fig. 4; Fig. 9, a sectional view on line 9—9 of Fig. 8 looking in the direction of the arrows; Fig. 10, a fragmentary sectional view taken on line 10—10 of Fig. 1, looking in the direction of the arrows; Fig. 11, a sectional plan taken on line 11—11 of Fig. 10; Fig. 12, an enlarged detail in perspective of the bearing member for the measuring vessel shown in Fig. 10; Figs. 13, 14 and 15, detail views showing the construction of the measuring vessel and associated parts, on an enlarged scale, Fig. 14 being a section on line 14—14 of Fig. 10, 75 looking in the direction of the arrows, Figs. 13 and 15, sectional plans taken on lines 13—13 and 15—15, respectively, of Fig. 14; Fig. 16, a sectional view of the devices employed for closing the dribble valve; Fig. 17, a sectional view on line 17—17 of Fig. 16, looking in the direction of the arrows; Fig. 18, a fragmentary sectional plan of one 80 end of the cylinder shown in the preceding two figures, and Fig. 19, a sectional view 85 illustrating the valve employed to close said cylinder.

Like characters of reference designate like parts in the several figures of the drawings.

Referring to the drawings, 25 designates the base of the machine, 26 a stationary table carried on the uprights 27, and 28 a shaft which is supported in a bearing 29 in the base 25 and extends through a central opening in the table 26. The upper 90 end of the shaft 28 takes a bearing in a sleeve 30 fitted in a boss 31 formed on the under side of the table and provided with a flange 32 which is bolted to the table. Feathered to the shaft 28 and bearing on 100 a projection 33 of the sleeve 30 is a drum 34 to which is secured the plate 35. Secured to the drum above plate 35 is a plate 36 which carries at its circumference a ring 37

2 forming the bottom of an annular filling tank 38. Within the filling tank 38 are a number of measuring vessels 39. A supply tank 40 located within the drum 34 is connected with the filling tank 38 by the pipes 41. The table 35 supports, in radial arrangement, a number of weighing scales designated generally by the numeral 42, there being one such scale for each measuring vessel 39, the scales being located directly under the measuring vessels. The cans or receptacles to be filled, one of these being shown at the right hand side of Fig. 1 and designated 43, are fed into the machine from a table 44 and placed one by one on the scales 42 by certain feeding devices designated by the numeral 45. The first operation of the machine is to counterpoise the empty cans as they are received on the scales. The cans are then successively filled, in the manner to be particularly described hereafter, and when they have received certain quantities of the liquid, measured by weight, the counterpoising movements of the scales put a stop to the filling operations. The cans are then discharged from the machine. As our present invention is not concerned with the weighing operations or the operations of feeding the cans to and discharging them from the machine, the mechanisms for performing such operations will not be described. These mechanisms are fully described in our co-pending application above referred to.

35 It will be understood that the invention contemplates the employment of a number of operating units, consisting each of a filling mechanism and its corresponding weighing mechanisms, these units being arranged radially about the central shaft 28. For clearness of illustration the general view of the machine given in Fig. 1 shows two of these units. The preferred arrangement of a larger number of units is indicated in the plan view given in Fig. 4.

40 The shaft 28 is driven by any suitable means. We have shown the shaft as provided with a worm gear 46 meshed by a worm 47 carried on a driving shaft 48.

45 The construction of the measuring vessels is shown particularly in Figs. 10 to 15, inclusive. The ring 37 which constitutes the bottom of the filling tank 38 is formed with a number of circular perforations directly above the scale pans of the several weighing mechanisms. In each of these perforations is fitted a bearing or pivot member 49, the upper surface of which is conical and which terminates in a stud 50. The bearing member 49 is formed with a flange 51 which is secured by bolts 52 to the under side of the ring 37. The measuring vessel 39 is provided with a conical bottom 53 provided with the internal flange 54 which fits around the stud 50. A spring 55 is interposed be-

tween the flange 54 and a washer 56, the latter being held in place by the set and lock nuts 57. The top 58 of the measuring vessel terminates in a hollow spindle 59 provided with lugs or wings 60 which extend into slots 61 formed in a hub 62. The hub is provided with projecting arms 63 and 64 (Figs. 1 and 4) and is supported by a bracket 65 formed on a ring 66 supported by a plate 67 secured to the upper end 70 of the drum 34. The bottom 53 of the measuring vessel is formed with two ports 68 and 69. The bearing member 49 is formed with the discharge port 70, with a recess 71 and a dribble port 72 connecting the recess 71 and the discharge port 70. The bearing member is also formed with a conical opening 73 in which is a valve 74 having a port 75 adapted to put the opposite ends of the dribble port into communication with each other when the valve is turned to a certain position. The valve 74 is mounted on a stem 76 which extends through a plate 77 secured to the under side of the bearing member 49 by the screws 78. A spiral spring 79 is interposed between the plate 78 and the valve 74. An arm 80 is secured to the end of the stem 76, being held thereon by the lock nut 81.

With the filling vessel in the position shown in Figs. 10, 14 and 15, the discharge port 70 and the dribble port 72 are closed. Port 68 stands above the recess 71 so that the measuring vessel is in communication with the filling tank 38. Consequently the liquid will stand at the same level in the measuring vessel and the filling tank. The filling tank is fed by pipes 41 from the central supply tank 40 and the liquid in the latter is kept at whatever level is necessary in order to measure off the desired amount of liquid in the measuring vessel. In the meantime the can to be filled has been placed upon the scale below the measuring vessel. At the proper time the measuring vessel is turned so as to close port 68 and bring port 69 into register with the discharge port 70. Communication between the measuring vessel and the filling tank is closed by this movement and the contents of the measuring vessel discharged into the can. The turning of the measuring vessel is brought about by the arm 63 coming in contact with the roller 82 (Figs. 4, 8 and 9). Preferably the roller is arranged so that it may be moved out of the path of the arm 63 in order that the flow of liquid may be stopped in case of accident. The roller is carried on the end of a rod 83 which is guided in brackets 84, 85, bracket 85 being secured to the under side of bracket 84 and the latter being attached to the under side of one of a pair of frame members 86 which extend across the machine and are secured at opposite ends to a ring 87 (Figs. 1 and 4) sup-

ported from the table 26 by the uprights 88. The rod 83 is connected by a link 89 with the end of an angular rock shaft 90 which is mounted in brackets 91 secured to the cross piece 86. The rock shaft has the handle 92. A lever 93 is pivoted to a bracket 94 on the under side of the cross piece 86 and connected with this lever is a rod 95 extending through a bracket 96 and provided with a block 97. A spring 98 is interposed between the roller and bracket 85. By turning the rocking member 90 roller 82 is raised out of the path of the arms 63 on the spindles of the measuring vessels. By means of the lever 93 the block 97 can be thrust under the rocking member so as to hold the roller in the raised position. The full line representation of the arm 63 at the left hand side of Fig. 4 shows the position of the arm before the discharge port from the measuring vessel is opened, that is, when the measuring vessel is in the position shown in Figs. 10, 14 and 15. The dotted line representation in the upper part of the figure shows the arm turned into position to discharge the contents of the measuring vessel into the can. The feathered arrows indicate the direction of rotation of the machine.

The measuring vessel is rotated back so as to close the discharge port and bring the filling port 68 over the recess 71 in the bearing member by the arm 64 coming into contact with a roller 99 supported on a bracket 100 secured to the ring 87. The liquid in the supply tank 40 and the filling tank 38 may be kept at a uniform or approximately uniform level in any desired manner either automatically or otherwise. As the first or volume fill is intended only to approximate the filling of the cans it is not essential that the level in the supply and filling tanks be kept exactly and accurately at the same point, the accurate measuring of liquid received in the cans being done through the operation of the dribble to be hereafter described. If automatic means be used for maintaining a given level in tanks 38 and 40 it may consist of the arrangements shown in Figs. 1, 4 and 5. *a* designates a float which is guided on a guide rod *b* in the tank 40. *c* designates a supply pipe provided with a valve *d*, the operating lever of which, *e*, is connected with the float *a* by a link *f*, the arrangement being the familiar one in which a downward movement of the float *a* opens valve *d* while an upward movement of the float closes this valve. Obviously any other preferred form of mechanism might be used for maintaining the liquid at the desired level.

By the operations above described given volumes of the liquid are successively discharged from the measuring vessels into the cans and the measuring vessels returned to their filling positions. The next operation

is to open the dribble port 72 so as to allow a small stream of the liquid to flow directly from the filling tank into the can. This is accomplished by shifting the valve 74 from the position shown in Figs. 10 and 14 ninety degrees so that its port 75 will register with the dribble port. This is done by the arm 80 coming into contact with a roller 101. Preferably this roller is also mounted so that it may be moved out of operative position. Referring particularly to Figs. 2, 3, 4 and 7, roller 101 is mounted on a pin 102 carried by an angular arm 103 pivoted at 104 to one of the uprights 88. The arm 103 is provided with a handle 105 and when in operative position bears against a stud 106. The roller can be moved out of the path of the arm 80 by turning the arm 103 over until it bears against the pin 107. A spring 108 holds the arm in either position.

The dribble port is closed, in the particular embodiment of our invention shown herein, by the balancing of the scale on which the can is supported. The scale beam carries an arm 109 which, when the scale is brought to a counterpoising position, sets in operation a vacuum actuated mechanism which returns the dribble valve 74 to the position shown in Figs. 10 and 14. It will be understood that the means employed for counterbalancing the can and its contents and so causing the movement of arm 109 forms no part of our present invention and therefore need not be described. These mechanisms are fully shown and described in the application of which the present case is a division.

The vacuum operated mechanism for shifting the dribble valve is preferably made up of the following parts: On the under side of the plate 36 (Figs. 1, and 16 to 19 inclusive) is a cylinder 110 provided at one end with the perforated head 111 and formed at the other end with the open neck 112. Within the cylinder is a piston 113, the rod 114 of which is connected by a link 115 with the short end 116 of the arm 80. When the arm 80 is turned by coming into contact with the roller 101, as above described, the piston 113 is drawn toward the head 111 of the cylinder. The neck 112 communicates by a port 117 with the interior of a smaller neck 118. A union 119 connects the pipe or hose 120 with the neck 118. The hose 120 is connected with an exhausting apparatus in the manner to be hereinafter described. The arm 109 carries at its upper end a valve 121 having a stem 122 which passes through a perforation in the arm 109 and through a sleeve 123. A spring 124 is interposed between the arm and the valve and a cotter pin 125 extends through the stem at the end of the sleeve. The upper end of the hose 120 is secured to a nipple 126 (Figs. 1, 5 and 6) in a ring 130

127. The ring 127 is fitted over a stationary ring 128 secured to the upper edge of the drum 34. The inner stationary ring 128 is formed with a groove 129 provided with 5 one or more recesses 130. Pipes 131 communicate with the recesses 130 and lead to the exhausting apparatus (not shown). When the piston 113 is moved back toward the head 111, which occurs when the dribble 10 port is opened, the valve 121 on the end of arm 109 stands away from the neck 112 shown at the right hand side of Fig. 1, and as soon as the port 132 in the ring 127, with 15 which the hose 120 communicates, comes opposite the groove 129 the exhaust apparatus sucks in outside air through the neck 112, port 117 and neck 118. When the arm 109 is moved to close the neck 112 the exhaust apparatus creates a partial vacuum in the cylinder 110 and draws the plunger 113 into 20 the position shown in Figs. 16 and 18. This movement of the plunger closes the dribble valve. The employment of the vacuum operated apparatus in this connection gives a 25 very quick closing movement to the dribble valve which is, of course, essential if the liquid is not to be wasted, and is preferable, in our opinion, to an electro-magnetic mechanism which if used on a machine handling liquids gives a great deal of trouble 30 because of the impairment of the insulation of the magnets which occurs when they get wet.

The operation of the apparatus will be 35 apparent from the above description. To briefly recapitulate, the can in each instance is placed under a measuring vessel at some time before the arm 63 on the spindle of the vessel comes into contact with the roller 40 82. The measuring vessel at this time is in communication with the filling tank and stands filled or partially filled with liquid. When the arm 63 meets roller 82 communication 45 between the measuring vessel and the filling tank is closed and the contents of the filling vessel discharged through the port 70 into the can. The measuring vessel is turned back to its filling position when arm 64 meets the roller 99. Shortly after 50 this the dribble port is opened by arm 90 meeting the roller 111. This movement draws the plunger in cylinder 110 back toward the head 111. As soon as the rotation of ring 127 brings the port 132 opposite the 55 groove 129 in the stationary ring 128 outside air is drawn in through the open end of neck 112. As soon as the valve on the end of arm 109 has closed the neck 112 the air is exhausted from cylinder 110 and the 60 piston 113 drawn to the forward end of the cylinder, which movement shifts valve 74 into a position which closes the dribble port. In case of any accident the rollers 65 82 and 101 which open the discharge ports from the measuring vessels and the dribble

ports can be moved out of the path of the arms 63 and 80 respectively, so that there will be no waste of the liquid.

We claim:

1. In apparatus of the character described, 70 the combination with a supply tank, of a measuring vessel provided with a rotatable element adapted in one position to put the vessel in communication with said tank and in another position to shut off communication with said tank and discharge the contents of said vessel therefrom, a movable support for the above specified apparatus, a stationary member, and means associated with said rotatable element adapted to be engaged by said stationary member so that 75 said element is rotated by said member. 80

2. In apparatus of the character described, 85 a volume filling mechanism comprising a conical pivot member having a filling port and a discharge port, a measuring vessel which is rotatably supported in upright position upon said pivot member and has its bottom perforated so as in one position to receive liquid from said filling port and in another position to discharge its contents through said discharge port, the other port in each case being closed, means for rotating said vessel, and a spring to hold said vessel in contact with said pivot member. 90 95

3. In apparatus of the character described, 100 a filling mechanism comprising a supply tank, a vessel having a conical bottom, a conical pivot member which projects into said supply tank and on which said vessel is mounted, said vessel and pivot member being formed with ports arranged so that in one position of the vessel it is in communication with the supply tank and in another is provided with a discharge, and 105 a spring adapted to keep the vessel in contact with said pivot.

4. In apparatus of the character described, 110 a filling mechanism comprising a supply tank, a vessel having a conical bottom, a conical pivot member which projects into said supply tank and on which said vessel is mounted, said vessel and pivot member being formed with ports arranged so that in one position of the vessel it is in communication with the supply tank and in another is provided with a discharge, a stud on said pivot member, an abutment on said stud, and a spring interposed between the abutment and said vessel for the purpose 115 described. 120

5. In apparatus of the character described, 125 the combination with a supply tank adapted to contain a liquid, of a pivot member in said tank which projects upward from the bottom thereof, a measuring vessel rotatably mounted on said pivot and immersed in the liquid in said tank, the measuring vessel and pivot member being formed with ports arranged so that in one position of the 130

measuring vessel it is in communication with said tank and in another position discharges its contents through said pivot member, a hollow spindle rigid with said vessel and 5 projecting above the level of the liquid in said supply tank and open at the top, and means for rotating the spindle.

6. In apparatus of the character described, the combination with a rotatable support, of 10 a supply tank on said support, a pivot member in said tank, a measuring vessel rotatably mounted on said pivot and adapted in one position to fill from said tank and in another position to discharge its contents, 15 a hollow spindle on said vessel, an arm on said spindle, and a stationary device with which said arm engages.

7. In apparatus of the character described, the combination with a rotary support for 20 the receptacles to be filled, of an annular tank arranged on said support above said receptacle, a plurality of rotary measuring vessels arranged in said tank and adapted at one position to fill from said tank and in 25 another position to discharge their contents into said receptacles, and means operated by the movement of the rotary support for shifting said measuring vessels from one position to the other.

30 8. In apparatus of the character described, the combination with a rotary support for the receptacles to be filled, of an annular tank arranged on said support above said receptacles, a plurality of pivot members 35 adapted to project into the tank through the bottom thereof, and formed with discharge ports and with filling ports, a plurality of measuring vessels rotatably mounted on said pivot members and adapted in one position 40 to be in communication with the filling ports, and in another position in communication with the discharge ports, hollow spindles on said vessels, and mechanism actuated by the movement of said rotary support for shifting said vessels from one position to the other.

45 9. In a machine of the character described, the combination with rotary supporting means, of filling apparatus comprising a discharge port, a valve to control said discharge port, and a vacuum actuated mechanism for moving said valve comprising stationary and rotating rings provided with air ports adapted to be brought into register.

50 10. In a machine of the character described, the combination with a tank, a measuring device adapted to receive liquid from said tank and discharge it into the receptacle to be filled, means constituting a dribble port adapted to discharge into said receptacle, a valve to control said port, and vacuum operated mechanism to shift said valve.

55 11. In a machine of the character described, the combination with rotating sup-

porting means, of a supply tank, a plurality of rotary measuring vessels adapted to be filled from said tank and to discharge into the receptacles to be filled, and a stationary device adapted to be engaged by 70 said measuring vessels so as to rotate them to their discharging positions; said device being mounted so as to be movable out of the path of said vessels, for the purpose described.

75 12. In apparatus of the character described, the combination with a movable support, of a supply tank on said support, a pivot member in said tank, a measuring vessel rotatably mounted on said pivot and adapted in one position to fill from said tank and in another position to discharge its contents, a hollow spindle on said vessel, an arm on said spindle, and a stationary device with which said arm engages.

80 13. In apparatus of the character described, the combination with a movable support for the receptacles to be filled, of a tank arranged on said support above said receptacles, a plurality of rotary measuring 90 vessels arranged in said tank and adapted in one position to fill from said tank and in another position to discharge their contents into said receptacles, and means operated by the movement of said support for shifting 95 said measuring vessels from one position to the other.

100 14. In apparatus of the character described, the combination with a movable support for the receptacles to be filled, of a tank arranged on said support above said receptacles, a plurality of pivot members adapted to project into the tank through the bottom thereof and formed with discharge ports and with filling ports, a plurality of 105 measuring vessels rotatably mounted on said pivot members and adapted in one position to be in communication with the filling ports and in another position to be in communication with the discharge ports, hollow spindles on said vessels, and mechanism actuated 110 by the movement of said support for shifting said vessels from one position to the other.

115 15. In a machine of the character described, the combination with a support for the receptacle to be filled, of filling apparatus comprising a port adapted to discharge into said receptacle, a valve to control said port, a cylinder adapted to be connected 120 with an exhausting apparatus, a piston in said cylinder connected with said valve, and means for causing said exhausting apparatus to exhaust the air from said cylinder so as to shift said piston and valve.

125 16. In a machine of the character described, the combination with a rotary support for the receptacle to be filled, of apparatus comprising a discharge port, a valve to control said discharge port, and a vacu-

um actuated mechanism for moving said valve comprising a cylinder having a port communicating with the atmosphere, a piston in said cylinder connected with said 5 valve, rotating and stationary rings having air ports adapted to be brought into register, the stationary ring being adapted to be connected with an exhausting apparatus and the rotary ring with said cylinder, and a 10 valve for closing the atmosphere port of said cylinder.

17. In a machine of the character described, the combination with a rotary support for the receptacle to be filled, of filling 15 apparatus comprising a discharge port, a valve to control said discharge port, and a vacuum actuated mechanism for moving said valve comprising a cylinder having a port communicating with the atmosphere, a piston 20 in said cylinder connected with said valve, rotating and stationary rings having air ports adapted to be brought into register, the stationary ring adapted to be connected with an exhausting apparatus and the rotary 25 ring with said cylinder, a valve for closing the atmosphere port of the cylinder, and means for moving the valve in the discharge port in the direction opposite to that described comprising a rocking member carried 30 on said valve, and a stationary member with which it is engaged by the rotary movement of said support.

18. In a machine of the character described, the combination with a support for 35 the receptacle to be filled, of a tank adapted to contain a liquid, a measuring vessel having a port below the level of the liquid in said tank through which said vessel is put into communication with the tank, said vessel being arranged so that when in communication with said tank it is filled to the level of the liquid therein, means providing a discharge port from the vessel to said receptacle, means for alternately opening and closing 40 communication between the tank and the measuring vessel and the measuring vessel and said receptacle through the aforementioned ports, means providing a dribble port from the tank to said receptacle, and a valve 45 to control said dribble port.

19. In a machine of the character described, the combination with a support for the receptacle to be filled, of a tank adapted to contain a liquid, a measuring vessel 55 immersed in the liquid in the tank and having a port below the level of said liquid through which the liquid from the tank may flow up into said measuring vessel to whatever level the liquid may stand in the tank, means 60 providing a discharge port from the vessel to said receptacle, means for alternately opening and closing communication between the tank and measuring vessel and the measuring vessel and said receptacle through the 65 aforementioned ports, means providing a

dribble port from the tank to said receptacle, and a valve to control said dribble port.

20. In a machine of the character described, the combination with a support for the receptacle to be filled, of a tank adapted 70 to contain a liquid, a rotatable measuring vessel immersed in the liquid in said tank having a port below the level of said liquid through which the liquid from the tank may flow into said measuring vessel, means providing a discharge port from the vessel to the receptacle, means for rotating said measuring vessel so as to alternately open and close communication between the tank and the vessel and the vessel and said receptacle 75 through said ports, means providing a dribble port from the tank to the receptacle, and a valve to control said dribble port.

21. In a machine of the character described, the combination with a movable 80 support for the receptacle to be filled, of a tank adapted to contain a liquid, a measuring vessel immersed in the liquid in said tank and having a constantly open air vent above the level of the liquid in the tank, an inlet port below the level of said liquid and an outlet port adapted to discharge into said receptacle, means actuated by the movement of said support for opening and closing 85 said ports in alternation, means constituting a dribble port from the tank to said receptacle, and a valve to control said dribble port.

22. In a machine of the character described, the combination with a movable 90 support for the receptacle to be filled, of a tank adapted to contain a liquid, a measuring vessel immersed in the liquid in said tank and having a constantly open air vent above the level of the liquid in said tank, an inlet port below the level of said liquid and an outlet port adapted to discharge into said receptacle, and means operated by the movement of said support for alternately opening 95 and closing communication between the tank and the measuring vessel and the measuring vessel and said receptacle through the aforementioned ports, said vessel being arranged so that when it is put into communication with the tank the liquid rises therein to the 100 level of the liquid in said tank.

23. In a machine of the character described, the combination with a movable support for the receptacle to be filled, of a tank adapted to contain a liquid, a rotatable measuring vessel immersed in the liquid in said tank and having a constantly open air vent above the level of the liquid in said tank, an inlet port below the level of said liquid and an outlet port adapted to discharge into said receptacle, and means operated by the movement of said support for rotating said vessel back and forth so as to alternately open and close communication between the tank and the measuring vessel and the measuring vessel 110 120 125 130

- sel and said receptacle through the aforementioned ports, said vessel being arranged so that when it is put into communication with the tank the liquid rises therein to the 5 level of the liquid in said tank.
24. In a machine of the character described, the combination with a movable support for the receptacle to be filled, of a tank adapted to contain a liquid, a conical 10 pivot member projecting up through the bottom of the tank, a measuring vessel rotatably mounted on said pivot, the pivot and the bottom of said vessel being formed with ports by means of which the vessel in one 15 position is in communication with said tank and in another position is provided with a discharge leading to said receptacle, and means operated by the movement of said support for rotating said vessel on the pivot.
- 20 25. In a machine of the character described, the combination with a movable support for the receptacle to be filled, of a tank adapted to contain a liquid, a pivot member projecting up through the bottom 25 of the tank, a measuring vessel rotatably mounted on said pivot, the pivot and the bottom of said vessel being formed with ports by means of which the vessel in one 30 position is in communication with said tank and in another position is provided with a discharge leading to said receptacle, means operated by the movement of said support for rotating said vessel on the pivot, said pivot member being formed with a dribble 35 port, and a valve to control said dribble port.
26. In a machine of the character described, the combination with a movable support for the receptacle to be filled, of a 40 tank adapted to contain a liquid, a pivot member projecting up through the bottom of the tank, a measuring vessel rotatably mounted on said pivot, the pivot and the bottom of said vessel being formed with 45 ports by means of which the vessel in one position is in communication with said tank and in another position is provided with a discharge leading to said receptacle, means operated by the movement of said support 50 for rotating said vessel on the pivot, said pivot member being formed with a dribble port; a valve to control said dribble port, and means operated by the movement of said support for shifting the valve in the dribble 55 port.
27. In a machine of the character described, the combination with a movable support for the receptacle to be filled, of a tank adapted to contain a liquid, a pivot 60 member projecting up through the bottom of the tank, a measuring vessel rotatably mounted on said pivot, the pivot and the bottom of said vessel being formed with ports by means of which the vessel in one 65 position is in communication with said tank and in another position is provided with a discharge leading to said receptacle, means operated by the movement of said support for rotating said vessel on the pivot, said pivot member being formed with a dribble port; a valve to control said dribble port, and means operated by the movement of said support for shifting the valve in the dribble port.
28. In a machine of the character described, the combination with a movable support for a receptacle, of a supply tank, means for maintaining liquid at a constant level in said supply tank, a measuring vessel, and means actuated when said support is moved for alternately putting said measuring vessel into and out of communication with said supply tank; said vessel being arranged so that when in communication with the tank it fills to the level of the liquid in said tank and being provided with a discharge port which is opened when communication is closed between the vessel and the tank and closed when communication is opened between the vessel and the tank.
29. In a machine of the character described, the combination with a movable support for a receptacle, of a supply tank, a measuring vessel, and means actuated when said support is moved for alternately putting said measuring vessel into and out of communication with said supply tank; said vessel being arranged so that when in communication with the tank it fills to the level of the liquid in said tank and being provided with a discharge port which is opened when communication is closed between the vessel and the tank and closed when communication is opened between the vessel and the tank.
30. In a machine of the character described, the combination with a rotary supporting means, of filling apparatus comprising a discharge port, a valve to control said discharge port, and a fluid pressure operated mechanism for moving said valve comprising stationary and rotating means provided with air ports adapted to be brought into register.
31. In a machine of the character described, the combination with a tank, a measuring device adapted to receive liquid from said tank and discharge it into the receptacle to be filled, means constituting a dribble port adapted to discharge into said receptacle, a valve to control said port, and fluid pressure operated mechanism to shift said valve.
32. In a machine of the character described, the combination with a support for the receptacle to be filled, of a tank adapted to contain liquid, a measuring vessel immersed in the liquid in the tank and having

- a port below the level of said liquid through which the liquid from the tank may flow up into said measuring vessel to whatever level the liquid may stand in the tank, means
- 5 providing a discharge port from said vessel to said receptacle, means for alternately opening and closing communication between the tank and measuring vessel and the measuring vessel and said receptacle through the
- 10 aforementioned ports, means providing a dribble port from the tank to said receptacle, a valve to control said dribble port, and fluid pressure operated mechanism for moving said valve.
- 15 33. In a machine of the character described, the combination with a support for the receptacle to be filled, of a tank adapted to contain a liquid, a rotatable measuring vessel immersed in the liquid in said tank
- 20 having a port below the level of said liquid through which the liquid from the tank may flow into said measuring vessel, means providing a discharge port from the vessel to the receptacle, means for rotating said measuring vessel so as to alternately open and close communication between the tank and the vessel and the vessel and said receptacle through said ports, means providing a dribble port from the tank to the receptacle,
- 25 30 a valve to control said dribble port, and
- fluid pressure operated mechanism for moving said valve.
34. In a machine of the character described, the combination with a movable support for a receptacle to be filled, of a tank having a discharge port, a valve to control said port, means actuated by the movement of the support for moving said valve to open the port, and a fluid pressure operated mechanism for moving said valve to its closed position.
35. In a machine of the character described, the combination with a rotary support, of a tank thereon provided with a discharge port, a valve to control said port, a fluid pressure operated mechanism on said support for moving said valve, a pipe leading to said fluid pressure operated mechanism, a ring which rotates with said support having a duct with which said pipe communicates, a stationary ring having a duct adapted to stand in communication with the duct in said rotating ring, and a pipe leading from the duct in said stationary ring.
